DRIER

Charles E. Morgenstern, St. Joseph, Mich., assignor to Nineteen Hundred Corporation, St. Joseph, Mich., a corporation of New York

Application September 12, 1941, Serial No. 410,515

7 Claims. (Cl. 34—133)

This invention relates to a drier, and more particularly, to a clothes drier of the rotating drum or tumbler type and having heating and air circulating means associated therewith.

In order to facilitate the drying of clothes and particularly clothes which have been washed by the so-called "home laundry" washing machine, it is desirable not only to remove the surplus water from the clothes such as may be done by a centrifugal extractor, but it is also desirable to further dry the clothes by circulating warm air thereover and therethrough. One of the features of the present invention is to provide a drying machine which includes a rotating drum which gently tumbles the clothes through a circulating stream of warm air.

It is an object of the present invention to provide a novel drying mechanism having the above referred to characteristics.

Another object of the present invention is to provide a drier having a rotating drum in which the articles to be dried are tumbled, and passing a stream of warm air through the drum while the articles are being tumbled therein.

A further object of the present invention is to provide a clothes drier of the rotating drum type in which the peripheral surface of the drum is heated and in which air is circulated axially through the drum.

Another and still further object of the present invention is to provide a novel method and means for drying clothes and other articles.

Still another object of the present invention is to provide novel driving mechanism for a rotating drum clothes drier.

Still another and further object of the present invention is to provide a novel means for heating and drying clothes and other articles.

The novel features which I believe to be characteristic of my invention are set forth with particularity in the appended claims. My invention itself, however, both as to its organization, manner of construction, and method of operation, together with further objects and advantages thereof, may best be understood by reference to the accompanying drawings, in which:

Figure 1 is an isometric view of a clothes drier incorporating the novel features of the present invention;

Figure 2 is a vertical sectional view of the drier taken on a plane passing from the front to the rear of the machine through the center thereof as taken along the line II—II of Figure 1;

Figure 3 is an irregular sectional view of the drier as taken along the line III—III of Figure 2;

Figure 4 is an enlarged fragmentary sectional view of one of the ribs in the rotating drum;

Figure 5 is an enlarged fragmentary sectional view through the door in the front of the machine;

Figure 6 is a view similar to Figure 2, but showing a modified form of drier; and,

Figure 7 is a rear vertical sectional view taken immediately inside the rear of the casing or shroud and looking toward the operating mechanism.

Referring now to Figures 1 to 5 of the drawings, which illustrate a preferred embodiment of the present invention, there is illustrated therein a rotary drum drier 10 having a shroud or casing 11 which encloses the operating parts of the mechanism. As may be seen best in Figure 1, the shroud or casing 11 has a sloping upper front wall portion 12 which is provided with a series of louvres 13 which extend not only over the greater portion of the sloping wall 12 but also extend down into the lower vertically extending wall portion 14. A clothes door 15 is provided in the sloping wall portion 12 and the central portion of this door 15 is also provided with a series of louvres 16 through which air may circulate. As may be seen best in Figures 2 and 3 the bottom of the drier 10 is closed off by a base plate 17 which has a short upstanding wall flange 18 and an outer lip portion 19. The side walls 20 of the casing or shroud 11 are provided along their lower edge with a complementary lip formation 21 which is welded or otherwise suitably secured to the lip portion 19 of the base 17.

The rear of the casing or shroud 11 is provided with a rear panel 141 having louvres 142 therein to permit the free influx of air in a manner presently to be described. The top of the casing or shroud 11 is provided with a top wall portion or cover plate 22. An inturned flange 23 is provided on the top wall portion 22 and is arranged to be seated on a complementary inturned flange 24 on the side walls 20 and on the complementary inturned flange 25 formed on the sloping front wall portion 12.

Rotatably mounted within the housing or shroud 11 is a drum 26 which is arranged to receive and gently tumble the clothes as they are being dried. The drum 26 includes a cylindrical metal shell 27 having radially outwardly turned flanges 28 and 29 at either end. The shell 27 is made of a solid, imperforate piece of metal in contrast to the usual wire mesh screen heretofore employed. This has been found to prevent accumulation of lint which is always present in

perforated cylindrical drums. A drum end or conical shell portion 30 is welded or otherwise suitably secured to the front end of the cylindrical shell 27, a radially outwardly turned flange portion 31 being provided for cooperation with the flange 28 on the shell 27. The drum end 30 has a large central aperture 32 which is defined by a forwardly turned flange 33. A portion of the conical drum end 30 adjacent the forwardly turned flange 33 is perforated as at 34 to permit free circulation of air therethrough, as well as through the central opening 32.

The rear end of the drum 26 is provided with an end ring plate 35 which is in the form of a flat annulus which is welded or otherwise suitably secured to the radially outwardly turned flange 29 on the cylindrical shell 27. The opening which is left by the annulus 35 is covered by a wire screen 36 which is retained in place by an angle ring 37. The drum 26 is carried on a rigid spider 38 which has three legs 39, which are riveted or otherwise suitably secured to the annulus 35. The spider 38 has a central hub portion 40. Although this spider 38 may be formed in a wide variety of manners without departing from the spirit and scope of the present invention, it is preferably formed of a plurality of parts, the hub portion 40 being one part and the radiating arms 39 being a separate and additional part. In such event, the central hub portion is provided with short stub arms 41 to which the long arms 39 are secured in any suitable manner.

The drum 26 is rotatably mounted on a short shaft 42 which in turn is carried in two spaced bearing members 43 and 44. The bearings 43 and 44 are carried on two pedestals 45 and 46, respectively. As is clearly shown in Figure 3, the bearing 44 is bolted to the pedestal 46 as at 47. The bearing 43 is similarly secured to its pedestal 45.

As an inspection of Figure 2 will clearly show, the shaft 42 is mounted at an angle to the base and more particularly is mounted along an axis perpendicular to the inclined front wall portion 12. To this end, the pedestals 45 and 46 are mounted on a pair of inclined ribs 48 which are U-shaped in cross section as shown in Figure 3, and which are riveted to the base plate 17 as at 49. It will, of course, be understood that the hub 40 is press-fitted or otherwise secured to the shaft 42 for rotation therewith and accordingly the drum 26 is arranged to be driven by the shaft 42 when the latter is positively rotated. Mounted on the shaft 42 between the bearings 43 and 44 is a propeller or fan 50. The propeller or fan 50 includes a plurality of blades 51 which are carried on a propeller hub 52. The hub 52 includes a pair of cylindrical central bearing sleeves 53 which permit independent rotation of the propeller or fan 50 on the shaft 42. That is to say, the propeller 50 is free to rotate or move at a different speed than the shaft 42. As will presently be brought out, the propeller 50 is arranged to be rotated at a much higher speed than the speed of rotation of the drum 26.

The driving mechanism for both the drum 26 and the propeller 50 is an electric motor 54 which is mounted on the base 17 with its drive shaft 55 disposed parallel to the driven shaft 42, which carries the drum 26. A U-shaped bracket 56 is mounted on a sub-base 57 and provides the necessary support and mounting for the motor. A flexible driving connection is provided between the driving member and the driven parts. More

specifically, the driving connection comprises a plurality of sheaves or pulleys and a flexible endless belt connection.

The direct drive to the fan or propeller will be described first. The motor drive shaft 55 is provided with a sheave 58. The hub 52 of the propeller 50 is provided with a peripheral V-shaped groove 59. An idler sheave 60 is mounted on the hub 61, which in turn is rotatably mounted on a stub-shaft 62. A journal bearing is provided by a bearing sleeve 63, which extends through the bore of the hub 61. The shaft 62 is rigidly carried on a take-up slide 64 which is freely mounted in a take-up slide guide 65. The take-up slide guide provides an enlarged passageway for the take-up slide which enables free movement of the take-up slide in all directions lying in the plane of the slide (that is, in a plane perpendicular to the axis of the shaft 62). A helical spring 66 is secured at one end to the lower stationary frame as at 67 and at the upper end to a finger 68. This in effect tends to pull the upper left corner of the take-up slide (as viewed from the rear) away from the motor 54 and downwardly toward the base 17 of the casing. An endless belt 69, having a generally V-shaped cross section, extends around the sheave 58 on the motor 54, the idler sheave 60, which is freely mounted on the stub-shaft 62 carried by the take-up slide 64, and the hub 52 of the propeller 50. The spring 66 maintains the endless belt 69 taut at all times and thereby enables the motor 54 to directly drive the propeller 50.

A reduced speed drive from the motor 54 to the drum 26 is provided by mounting a large sheave 70 rigidly on shaft 42 and by providing a V-shaped peripheral groove 71 in the hub 61 which carries the sheave 60. An endless belt 72 extends around the large sheave 70 and the groove portion 71 of the hub 61, as is clearly shown in the drawings. By virtue of the downward pull of the balancing spring 66 on the take-up slide 64 the stub-shaft 62 which carries the hub 61 is urged downwardly to maintain the endless belt 72 taut at all times. Due to the fact that the large sheave 70 is many times the diameter of the grooved hub portion 71 it will at once be understood that a reduced speed drive is provided for the drum 26.

The take-up slide and the manner in which it tensions two endless belts in different directions is one of the important novel features of the present invention.

Means for heating the drum 26 and for heating the air forced therethrough is provided in the preferred embodiment of the invention by an electric element 73 which is in the form of a band extending around the outer peripheral surface of the metal drum 26. A band of insulating material 74 extends around the drum over the heating element 73. The assembly is completed by a steel clamp band 75 which extends around the insulation 74 and clamps both the insulation and the electric heating element 73 to the drum 26.

Mounted on the rear of the drum frame are a pair of commutator rings 76 and 77. The opposite ends of the heating element 73 are electrically connected to the outer and inner slip rings 76 and 77 by conductors 78 and 79, which extend across the outer surface of the drum 26 to the rear end thereof (not shown) and then down one of the channel shaped arms 39. The slip rings 76 and 77 are engaged by a pair of contact fingers 75 (only one of which is shown), which are in

turn connected to a suitable source of electric power for heating the heating element 73.

In order to prevent heat losses on the exterior side of the drum 26, the outer peripheral surface of the drum is covered with an insulating material 81, such as shredded asbestos, rock wool, or the like, which is held in place by a pair of steel bands 82.

In order to prevent the clothes which are placed in the rotating drum 26 from becoming wadded up or bunched, a plurality of ribs 83 are provided on the inner surface of the drum 26. These ribs extend parallel to the axis of rotation of the drum and project radially inwardly from the inner surface of the drum 26. The ribs 83 are preferably formed of sheet metal stock which is folded in the manner as is clearly shown in Figure 4. More particularly, the sheet metal stock is folded in such a manner as to provide spaced side wall portions 84, a rounded inner end 85 and overlapping marginal portions 86. The overlapping marginal portions are riveted to the peripheral wall 27 of the drum 26 as at 87. A clip 88 is provided at each end of each of the ribs 83 which firmly hold the ribs 83 in place. The clip 88 is of U-shape and has a central portion 89 which is riveted to the ends of the drum as at 90. The legs of the U-shaped clip 88 are riveted to the side walls 84 of the rib 83 as at 91.

The clothes door 15 in the sloping front wall 12 which affords access to the interior of the rotating drum 26 is hingedly mounted on the shroud or casing 11 as at 92. Two hinges are preferably provided along one vertical edge of the door 15. A pair of rubber bumpers 93 are provided at the opposite side of the door which abut against the sloping front wall 12 of the shroud 11. While a lock or fastening means may be provided for the door if desired, preferably no latch or other locking mechanism is employed. It has been found that the door will be maintained closed under all normal operating conditions due to the fact that the front wall portion on which the door is mounted is sloping, and the door is consequently held in its closed position by gravity. If there is any stoppage or restriction of air flow for any reason whatsoever, or if some unusual condition tries to force the clothes out of the drum they will open the door automatically and thus avoid serious damage to the machine.

The machine performs its drying operation on any laundered clothes or the like in the following manner:

The clothes are placed in the drum 26 after the heating element 73 has been energized for a sufficient length of time to raise the temperature within the drum 26. The motor 54 is then connected which causes the drum 26 to rotate at relatively slow speed while simultaneously it causes the propeller 50 to rotate at high speed. The rotation of the drum 26 causes a gentle tumbling action of the clothes contained therein. Due to the relatively high velocity air stream passing axially through the drum there is a tendency for the clothes to be fluffed or billowed out as they fall from a point near the top of the drum. The air passing axially through the drum is heated due to the fact that the peripheral surface 27 of the drum 26 has been heated by the electric heating element 73. This warm stream of air dries the clothes within the drum. It has been found that due to the tumbling action of the clothes none of the clothes remain in continuous contact with the inner surface of the drum 26, and for that reason there is no danger of burning or

scorching any of the clothes contained therein. After the clothes have been dried, the motor 54 is deenergized and after the door 15 has been opened the clothes are removed.

In Figures 6 and 7 of the drawings, I have illustrated a different embodiment of the present invention. The principal differences between this embodiment of the present invention and that illustrated in Figures 1 to 5, inclusive, are the manner in which the air stream is heated and the manner in which the drum is rotated.

The drying mechanism of the second embodiment of the present invention is contained within a housing or shroud 100 which includes side walls 101, a front wall 102, a top plate 103, and a bottom plate or base 104. The front wall 102 is equipped with a door 105 which is hingedly mounted in any suitable manner (not shown) to the front wall 102. A clothes receiving drum 106 is rotatably mounted within the housing 100 for rotation about a horizontal axis. More specifically, the drum 106 is supported on two pairs of flanged wheels 107 and 108 which are mounted on rotatable shafts 109 and 110, respectively. The flanged portion of the wheels 107 and 108 constrain the drum 106 and keep it from moving in an axial direction. The location of the wheels 107 and 108 themselves keeps the drum 106 from moving transversely of the axis of rotation of the drum 106. As will be seen from the above explanation, a floating support for the drum 106 is provided.

The shafts 109 and 110 are rotatably carried in bearings 111 and 112 which are carried on suitable pedestals 113 and 114. It will, of course, be understood that a set of bearings 111 and 112 and associated pedestals 113 and 114 are provided for each of the shafts. The wheels 107 and 108 are rigidly mounted on their respective shafts 109 and 110 and are accordingly arranged to be driven thereby. Each shaft 109 and 110 overhangs and extends beyond its rear bearing 112 and has mounted thereon a sheave 115 and 116, respectively.

A stationary spider frame 117 is mounted to the rear of the drum 106. The spider 117 includes a circular band 118 and a plurality of radially extending arms 119 which are connected at their inner ends to a second circular band 120. The outer circular band 118 is welded or otherwise suitably secured to a structural frame member 121 which in turn is mounted on a pair of channel members 122. As an inspection of Figure 6 will clearly show, the outer ring 118 is of much greater width than the width of the arms 119 or the width of the inner circular band 120.

An electric motor 123 is mounted within the inner circular band 120 of the spider 117 and is fully and completely supported thereby. The drive shaft 124 of the motor 123 is provided with a sheave 125 of relatively small diameter as compared with the diameters of the sheaves 115 and 116. An endless belt 126 extends around the motor sheave 125 and the large sheaves 115 and 116. Rotation of the motor drive shaft 124 thereby causes rotation of the drum supporting shafts 109 and 110 which in turn through the wheels 107 and 108 cause rotation of the drum 106. The belt 126 is tensioned by an idling sheave 127 which is carried on a pivotally mounted arm 128. The weight of the arm 128 and the sheave 127 cause the endless belt 126 to be tensioned in a manner well known to those skilled in the art. The gravity action of the arm 128 and the sheave

127 may, if desired, be supplemented by spring biasing means.

Means for circulating air through the drum 106 is provided for by a propeller 129 which is tightly secured to the motor drive shaft 124 which also extends out the front end of the motor. It will thus be understood that the propeller 129 rotates at the same speed as the motor.

Means for heating the air stream is provided for by a heating spider 130 which is secured by angle brackets 131 to the inner circular band 120 of the stationary spider frame 117. The spider 130 is heated by an electric heating element 132 which extends around the outer peripheral surface of the spider 130. The electrical heating element 132 is clamped in place by a steel band 133 the ends of which are held together by a bolt 134. The spider or grid 130 is formed of iron or other suitable heat conducting metal, such that air passing therethrough and thereover will be heated thereby. The grid or spider 130 is, of course, directly heated by the electric heating element 132. While no electrical connections are shown for the electric heating element 132, it will, of course, be understood that this heating element is arranged to be connected to a suitable source of electrical energy.

The rotatable drum 106, as in the preferred embodiment of the invention, is provided with a plurality of ribs 135. In this particular embodiment of the invention four ribs are intended to be employed within the rotating drum 106, but it is of course to be understood that any number may be employed without departing from the spirit and scope of the present invention. These ribs 135 may be secured to the end plates or rings 136 and 137 of the drum 106 in the same manner as that described in connection with the preferred embodiment of the present invention. An annular ring 138 is provided on the drum 106 at the front end. The annular region between the ring 138 and the annular wall portion 136 is covered by a screen 139 a circular angle iron 140 being provided to clamp the screen 139 to the annular wall portion 136.

In order to dry clothes shown in the unit in Figures 6 and 7, the door 105 is opened and the clothes inserted in the rotatable drum 106. The heating element 132 is energized which causes the spider or grid 130 to become hot. Since the propeller 129 and the grid 130 are both within the interior of the outer annular ring or cylindrical shell 118, it will be observed that air is sucked over the heating element and then impelled axially through the rotatable drum 106. Energization of the motor 123 rotates the propeller 129 at high speed and rotates the drum 106 at relatively slow speed. It will be understood that the air is then exhausted through suitable openings 143 in the front of the housing in a manner similar to that described above in reference to Figure 2. Rotation of the drum 106 causes a tumbling action of the clothes contained therein. Due to the blast of warm air passing axially through the drum, the clothes are billowed and fluffed as they fall from the side of the drum to the bottom during rotation.

While I have shown and described certain particular embodiments of my invention, it will, of course, be understood that I do not wish to be limited thereto, since many modifications may be made, and I, therefore, contemplate by the appended claims to cover all such modifications as fall within the true spirit and scope of my invention.

I claim as my invention:

1. A clothes drier comprising a supporting frame, a clothes receiving drum having a completely imperforate generally cylindrical wall, and having openings at both ends, said drum being rotatably mounted on said frame, power means carried by said frame for rotating said drum, heating means extending peripherally around and extending axially of at least a portion of said generally cylindrical wall, means supplying energy to the heating means, a propelling means in proximity to one end of said drum for circulating air axially therethrough, and means for driving said propelling means from said power means.

2. A clothes drier comprising a supporting frame, a shaft mounted for rotation on said frame, a clothes receiving drum fixedly mounted on said shaft in a cantilever fashion, said drum having a substantially imperforate peripheral surface and axially aligned openings at both ends, the axis of rotation of said drum being disposed at an oblique angle to the horizontal, a casing surrounding said drum and having a door therein opposite an end of said drum for depositing and removing clothes from said drum, said casing having openings therein opposite said openings in said drum, including openings in said door, so as to provide a substantially unobstructed passage for air through said casing and drum, means including a rotatable propeller mounted on said shaft for moving air axially through said drum to the atmosphere, means to heat said air prior to its discharge from said drum, and power means carried by said frame for rotating said shaft and said propeller.

3. A clothes drier comprising a supporting frame, a clothes receiving drum having openings at both ends, a driven shaft rotatably mounted on said frame and secured to and carrying said drum, means for rotating said shaft, air heating means for heating the interior of said drum, and a propeller rotatably mounted on said driven shaft and arranged to cause air to pass axially through the openings in the drum while it is rotated, and means for rotating said drum and said propeller.

4. A clothes drier comprising a supporting frame, a clothes receiving drum having openings at both ends, a driven shaft rotatably mounted on said frame and secured to and carrying said drum, means for rotating said shaft, air heating means for heating the interior of said drum, and a propeller rotatably mounted on said driven shaft and arranged to cause air to pass axially through the openings in the drum while it is rotated, rotating driving means, and power transmission means between said driving means and said drum and between said driving means and said propeller for rotating said drum at relatively slow speed and for rotating said propeller at relatively high speed.

5. A clothes drier comprising a supporting frame, a clothes receiving drum having a completely imperforate heat conducting generally cylindrical body portion and having openings only at the ends thereof, said drum being rotatably mounted on said frame, power means carried by said frame for rotating said drum, a heating element mounted on the exterior surface of said cylindrical body portion of said drum, means supplying energy to said heating element, an insulating covering extending over said heating element and the peripheral surface of said drum for reducing heat radiation losses exteriorly

of the drum, a propelling means in proximity to one end of said drum for circulating air axially therethrough, and means for driving said propelling means from said power means.

6. A clothes drier comprising a supporting frame, a clothes receiving drum having substantially axially aligned openings at the ends thereof, said drum being rotatably mounted on said frame about an axis inclined to the horizontal, means including a rotatable shaft for rotating said drum, a shroud covering said drum and said rotating means, said shroud having a sloping front wall portion lying in a plane substantially perpendicular to the axis of rotation of said drum, said front wall portion having a clothes door therein for depositing and removing clothes from said drum, said shroud having openings therein opposite those in the ends of said drum, including openings in said door so as to provide a substantially unobstructed passage for air through said shroud and drum, means including a rotatable propeller mounted on said shaft within said shroud adjacent the rear wall of said shroud for moving air through the openings in said drum and through said shroud openings to

the atmosphere, means to heat said air prior to its discharge from said drum, and power means carried on said frame for rotating said shaft and said propeller.

5 7. A clothes drier comprising a supporting frame, a clothes receiving drum having axially aligned openings at the ends thereof, said drum being rotatably mounted on said frame about an axis inclined to the horizontal, means for rotating said drum, a shroud covering said drum and said rotating means, said shroud having a sloping front wall portion lying in a plane substantially perpendicular to the axis of rotation of said drum, said front wall portion having a clothes door therein for depositing and removing clothes from said drum, said shroud having openings therein opposite those in the ends of said drum, including openings in said door so as to provide a substantially unobstructed passage for air through said shroud and drum, means for moving air through the openings in said drum and through said shroud openings to the atmosphere, and means to heat said air prior to its discharge from said drum.

CHARLES E. MORGENSTERN.
